UNITED STATES PATENT OFFICE

HARRY A. DAVIS, OF HOPEDALE, MASSACHUSETTS, ASSIGNOR TO DRAPER CORPORATION, OF HOPEDALE, MASSACHUSETTS, A CORPORATION OF MAINE

AUTOMATICALLY-THREADING LOOM SHUTTLE

Application filed May 1, 1930. Serial No. 448,817.

This invention relates to automatically threading loom shuttles and is more particularly directed to means for preventing the thread tensioning devices from becoming disassociated with the shuttle during weaving.

In the patent to Hutchins, No. 1,723,423, August 6, 1929, there is shown and described a thread tensioning mechanism comprising two members normally under the influence of resilient means tending to separate the two members to tension and take up slack in the thread. The tensioning members described in the above-mentioned patent have their end portions pivoted to the opposite walls of the shuttle recess or thread passage and intermediate the end portions of each tensioning member there are bends and thread engaging portions which act under the resilient means to take up slack in the thread and maintain substantially uniform tension.

During the weaving operation the shuttle is subjected to sudden impulses during the picking movement and then a sudden stoppage of the shuttle as it finishes its flight and is arrested in the opposite shuttle box. These conditions have at times caused the pivotal end portions of the tensioning members to be thrown from their pivotal connection with the opposite walls of the thread passage, and one of the purposes of the present invention is to provide a guard which shall overcome this difficulty and maintain the pivoted tensioning members properly associated with the shuttle.

The invention and novel features thereof will best be made clear from the following description and the accompanying drawings of one good form thereof.

In the drawings:

Fig. 1 is a top side perspective view of a shuttle containing the present invention, some of the parts being broken away for clearness of illustration; and

Fig. 2 is a cross-section of the shuttle at the forward end portion of the tensioning members showing in section the pivotal connection of the tensioning members with the side walls of the shuttle recess or thread passage.

The shuttle is of the automatically replen-

ishing type in which the filling carrier or bobbin is changed from time to time and wherein the shuttle becomes threaded during its picking movements. Such shuttles are usually provided with a longitudinal thread passage or recess at the threading end of the shuttle beyond the bobbin chamber, and ordinarily a threading block is provided to facilitate the entrance of the thread to the longitudinal thread passage on replenishment of filling.

The shuttle 1 is provided with the bobbin chamber 2 and forward of the bobbin chamber is the recess or thread passage 3 which communicates with the side delivery eye 4, as usual in this type of shuttle. Overhanging the thread passage is the threading block 5 having a down-turned portion 6 separated from the opposite wall of the thread passage to enable the thread to pass into the longitudinal thread passage on replenishment of filling, and these parts may be of the usual character.

The thread tensioning members may be of the same general character as more fully shown and described in the Hutchins patent, above noted, and each of the tensioning members 7 and 8 is provided with the thread engaging portions 9, 10, and between the thread engaging portions 9 of the tensioning member 7 there is a loop 11 extending towards the adjacent end of the shuttle, and similarly, there is a forwardly extending loop 12 on the other tensioning member 8, substantially in all respects the same as in the Hutchins patent.

Each of the tensioning members 7 and 8 has its ends pivotally mounted in the opposite side walls of the thread passage, preferably in blocks 13 and 14, so that they may move about their pivotal connection with the shuttle under the pull of the thread and act yieldingly upon the thread through the resilient means, such as the rubber band 15, to take up slack.

Adjacent the pivotal points of the tensioning members each is provided with an off-set portion, that is, from the pivotal point of each tensioning member a limb of that member is turned towards the bobbin cham-

ber thereby forming an off-set adjacent each pivot. Such off-set portion of the tensioning member 7 at one side of the bobbin chamber is shown at 16, while at the opposite side of the bobbin chamber adjacent to the opposite pivot the off-set of said tensioning member is indicated at 19. Likewise, the tensioning member 8 has an off-set portion 18 adjacent one pivot of said member and an off-set portion 17 adjacent the opposite pivot. The construction thus briefly described may be the same in all respects as shown and described in the Hutchins patent.

In applying the tensioning members to the shuttle the pivotal end portions thereof are sprung inwardly and then inserted in a recess in the blocks 13, 14 all as is more fully described in the Hutchins patent.

In accordance with the present invention, a guard is provided which overlies the off-set portions of the two tensioning members adjacent their respective pivots, and, as shown in the present instance of the invention, the guard comprises a loop portion 20 which may be secured to the shuttle at one side of the longitudinal thread passage by a screw or bolt 21. Extending downwardly from the upper portion of the guard is a leg 22 which, as indicated, overlies the off-set portions 17 and 19 of the two tensioning members adjacent their pivotal mountings.

The guard is further provided with a leg portion 23 at the opposite side of the thread passage which overlies the off-set portions 16 and 18 of the two tensioning members adjacent the opposite pivots, with the result that all danger of the tensioning members becoming detached from the shuttle during weaving is obviated.

In the present instance of the invention, the two leg members 22 and 23 of the guard are connected at 24 by a bridge which extends below the pivotal mounting of the two tensioning members, and in order that the guard containing the leg portion 23 may be held in operative relation with the off-set portions 16 and 18 of the tensioning members and offer no obstruction to the thread during the shuttle threading operation, the upper end of the leg portion 23 is turned outwardly at 25 and then extended downwardly on the side of the off-set portions 16 and 18 remote from the leg 23, and at its lower portion the bend 25 is entered into a recess in the lower wall of the shuttle, as at 26.

Thus, during the weaving operation, notwithstanding the shocks to which the shuttle is subjected, the pivotal ends of the two tensioning members are prevented from disengagement from their pivotal mounting at the sides of the longitudinal thread passage.

As hereinbefore noted, the tensioning members are under the influence of a yielding element, such as the band 15, and in the present instance the band 15 is supported

from a part of the guard. Such supporting portion of the guard is indicated at 29 and consists of a leg portion having the supporting bends 30 and 31 about which the loop of the band 15 passes and by which the band 70 may be supported in its tensioning position. As set forth in the Hutchins patent, the resilient band 18 passes under a bend of the tensioning member 8 and over a corresponding bend in the tensioning member 7, with the 75 result that there is a normal tendency of separation between the tensioning members, as indicated in Fig. 1.

Should the pivotal mounting of one or the other of the tensioning members become detached from the shuttle during weaving, the entire function of the tensioning members is destroyed, and the present invention provides a simple yet effective means for holding the pivotal points of the tensioning members seated in the supporting blocks 13, 14, or the side walls of the longitudinal thread passage, with the result that the tensioning members act continuously, as described in the Hutchins patent, throughout the weaving operation. 80

What is claimed is:

1. An automatically threading loom shuttle having a longitudinal thread passage, a thread tensioning member pivotally mounted at its ends at opposite sides of the thread passage and provided with an off-set adjacent each pivot, a guard secured to the shuttle and having leg portions, one at each side of the thread passage, overlying the off-sets of the pivoted tensioning member to prevent disengagement of the pivots from the shuttle during weaving. 95

2. An automatically threading loom shuttle having a bobbin chamber, a longitudinal thread passage and side delivery eye, thread tensioning members pivoted in the longitudinal passage and each having an off-set portion adjacent its pivot, and a guard secured to the shuttle and having a leg portion overlying the two off-set portions of the tensioning members adjacent the pivots thereof to prevent accidental detachment of the pivots from the shuttle during weaving. 100

3. An automatically threading loom shuttle having a forwardly extending thread passage and a side delivery eye communicating therewith, a pair of thread tensioning members pivoted at their ends in the opposite side walls of said passage and each provided with an off-set bend adjacent its pivots, and a guard constituted as a leg secured at each side of the thread passage and overlying the off-set bends of the tensioning members to prevent accidental detachment of the pivots 110 from the shuttle during weaving. 120

4. An automatically threading loom shuttle having a bobbin chamber, a longitudinal thread passage, and a side delivery eye, thread tensioning members having their ends pivot- 130

ally mounted at opposite sides of the longitudinal passage, and a pivot guarding leg extending upwardly at each side of the thread passage over the pivotal portions of the tensioning members to prevent accidental detachment of the pivotal portions of said tensioning members from the shuttle during weaving.

5. An automatically threading loom shuttle having a longitudinal thread passage and a side delivery eye, a pair of thread tensioning members pivotally mounted in the opposite walls of the thread passage and having thread engaging loops, a guard secured to the shuttle and having pivot guarding leg portions, one at each side of the longitudinal thread passage, overlying the side portions of the tensioning members adjacent their pivots to prevent disengagement of the latter from the shuttle during weaving.

10. An automatically threading loom shuttle having a longitudinal thread passage, a thread tensioning member pivotally mounted at its ends at opposite sides of the thread passage and provided with an off-set adjacent each pivot, a guard secured to the shuttle and having leg portions, one at each side of the thread passage, overlying the off-sets of the pivoted tensioning member to prevent disengagement of the pivots from the shuttle during weaving, and a bridge connecting the two leg portions of the guard.

15. An automatically threading loom shuttle having a bobbin chamber, a longitudinal thread passage and side delivery eye, a thread tensioning member having its ends pivotally mounted at opposite sides of the thread passage and having intermediate bends for engagement with the thread and an off-set adjacent each pivot, yielding means acting on the tensioning member to take up slack, a fixed guard having a leg at one side of the thread passage overlying the adjacent off-set portion of the tensioning member, a leg at the opposite side of the thread passage overlying the adjacent off-set portion of the tensioning member, and a bridge connecting the two legs of the guard below the pivots of the tensioning member.

20. An automatically threading loom shuttle having a bobbin chamber, a longitudinal thread passage and side delivery eye, a thread tensioning member having its ends pivotally mounted at opposite sides of the thread passage and having intermediate bends for engagement with the thread and an off-set adjacent each pivot, yielding means acting on the tensioning member to take up slack, a fixed guard having a leg at one side of the thread passage overlying the adjacent off-set portion of the tensioning member, a leg at the opposite side of the thread passage overlying the adjacent off-set portion of the tensioning member, a bridge connecting the two legs of the guard below the pivots of the tension-

ing member, and a support for said yielding means constituted as part of the guard.

25. An automatically threading loom shuttle having a bobbin chamber, a longitudinal thread passage and a side delivery eye, a thread tensioning member having its ends pivotally mounted at opposite sides of the thread passage and having an intermediate portion for engagement with the thread and an offset adjacent the pivot, a fixed guard having a leg at one side of the thread passage overlying the adjacent offset portion of the tensioning member to prevent disengagement of the pivot of the tensioning member from the shuttle, yielding means acting on the tensioning member to take up slack in the thread, and a support for the yielding means constituted as part of the guard.

30. In testimony whereof, I have signed my name to this specification.

HARRY A. DAVIS.
